B. BUNCE,
Rotary Steam Valve.
No 21,813. Patented Oct. 19, 1858.

UNITED STATES PATENT OFFICE.

BENJN. BUNCE, OF NEW YORK, N. Y.

CUT-OFF VALVE FOR STEAM-ENGINES.

Specification of Letters Patent No. 21,813, dated October 19, 1858.

To all whom it may concern:

Be it known that I, BENJAMIN BUNCE, of New York, county of New York, and State of New York, have invented certain new 5 and useful Improvements in the Cut-Off Valves of Steam-Engines; and I do hereby declare that the following is a full, clear, and exact description of the same, reference being made to the annexed drawing, making 10 a part of this specification, in which—

Figure I is a longitudinal vertical section through the steam chest. Figs. II, III and IV are of parts in detail.

Similar letters refer to similar parts 15 throughout.

My invention is adapted to work in connection with any of the ordinary forms of slide-valves.

The improvement lies chiefly in the mode 20 of admitting the steam to the slide-valve, and consists in attaching to the slide itself a tube which communicates from its interior with the induction passage on the face of the slide, and which tube is slotted on its 25 sides to receive steam from the steam-chest, in which it is situated. The slotted tube is surrounded by a sleeve or cylinder, which is also slotted, and partial rotation is given to the sleeve so that the slots in the two 30 may either coincide, or may close each other, as required, by stops fixed within the chest and against which stops a pin projecting from the sleeve is brought to strike as the tube and its sleeve are carried along by the 35 movement of the slide-valve to which those are affixed.

I am aware that a cut-off has been made with a slotted tube and cylindrical slotted seat over it, yet this has not been combined 40 with the slide-valve so as to be moved along with it, without the requirement of an independent set of connections to give it its play.

My improvement will be readily understood 45 by the following description of the construction.

The slide-valve is shown at A in Figs. I and II and has the usual openings upon its face for admitting and exhausting steam, as 50 (b b'). At each side rises a hollow post A; the channels in which communicate with the induction passages (b). Into these posts a cross tube is fitted so as to fill up the holes shown in their tops, and is so secured as to 55 make a steam tight joint around the ex-

ternal edges, the tube itself being closed at both ends. This tube is seen at C, Fig. I, and is also represented detached in Fig. III. The apertures are narrow slots extending lengthwise of the tube, as at C', and may be distributed equally around the tube, as shown. The aggregate area of the whole should be equal to that of the induction ports. This tube forms the cut-off valve-seat; the cut off valve is a cylinder or sleeve 60 divided lengthwise into two segments and is represented at D. The bore of this is such as to fit upon the surface of C, and through this cylinder is also a series of slots D', of like capacity and shape with those 65 on C. Each segment of the valve has a flange set off as seen at (e), for the purpose of clamping the two parts upon the tube, a space being left between to form a slot-opening in each side. Consequently, the two 70 parts of the sleeve are not exactly semicylinders.

Fig. I exhibits a sectional view of the cut-off valves in place within the steam-chest. In valve No. 2, the position shown is that 80 wherein the steam apertures in C and D coincide, while the valve No. 1 is so turned as to exhibit the slots in C' closed by the cylinder D.

The halves of D are clamped upon the 85 tube C by screws passing through the set off flanges (e), or they may be kept together by a spring which shall be constantly acting to draw them toward each other, serving to keep always a tight surface by closing up as 90 fast as the wear requires. There is a pin (i) projecting from the cylinder D by which its vibratory motion is obtained.

The operation is as follows: The valves A, 95 playing back and forth as usual, open the steam and exhaust ports on the great cylinder, and the cut-off is of course carried along with it. As these movements take place the pin (i) strikes two stops before the slide-valve reaches the end of its stroke. 100 By this means the cylinder D is turned partially around on its tubular axis C which forms its seat. These stops are on opposite sides of (i) and are represented by (O) and (O'). The valves are shown at half-stroke; 105 No. 2 is over the exhaust port and No. 1 over the steam port. The pin (i) strikes the stop (O) and the cut off is thus turned so as to make both sets of apertures viz. D' and C', coincide. The pin on valve No. 110

1 is shown as being struck by the stop (O'), so that D has been turned sufficiently to close the aperture C', the cut-off thereby being effected. The piston now travels for 5 the remainder of its stroke and the valves are reversed. As (b) of valve No. 2 comes over its steam port (s), steam will pass through all the slots D' and C' from the steam-chest, then through the tube C and 10 down the hollow posts A' and through the valve into the cylinder of the engine, the valve No. 1 being at that time over its exhaust port. The pin (i) of No. 2 will now be brought so as to strike (O') and the cut-off effected by turning D, while the pin (i) on No. 1 strikes the stud (O) and opens its steam passages. The degree of expansion will be regulated by the position of (O'), for the cut-off will be sooner or later according 15 to its position in the path of the slide valve. When therefore a variable cut-off is desired (O') is made, adjustable by any suitable mechanical contrivance and as

shown in Fig. I. The stops (O) are always fixed.

25

I claim—

Combining with a slide valve of ordinary character, a cut-off valve, constructed substantially as described—that is to say—the slotted tube secured in a fixed position upon the slide, said tube having its ends so closed that the steam shall pass to the valve through the slots, and having also upon it a cylinder, slotted in like manner, capable of being revolved thereon so that the opening and closing of the slotted passages shall be effected by the action of the slide-valve itself in carrying the cut-off to and from the stops set to intercept the revolving cylinder, as set forth.
